UNITED STATES PATENT OFFICE.

AUGUST KAMPE, OF MOSCOW, RUSSIA.

PIANO-ACTION.

SPECIFICATION forming part of Letters Patent No. 367,210, dated July 26, 1887.

Application filed January 29, 1887. Serial No. 225,929. (No model.)

To all whom it may concern:

Be it known that I, AUGUST KAMPE, a subject of the Czar of Russia, residing at Moscow, Russia, have invented certain Improvements 5 in Piano-Actions, of which the following is a specification.

My invention consists of improvements in piano actions, designed with the view of combining strength and simplicity of construction 10 with precision of action.

In the accompanying drawings, Figure 1 is a side view of one form of my improved mechanism. Fig. 2 is a view of a modification. Fig. 2^a illustrates a modification of a detail of 15 the construction. Fig. 3 is a view illustrating the application of my improvements to an upright piano, and Fig. 3^a is a view of a modification in one of the details.

Referring to Fig. 1, A is the rear end of one 20 of the keys, and on this is mounted a regulating-plate, B, adjustable by means of screws. To this regulating-plate is pivoted the angular lever b, having a step, o, on which normally rests the rod a, carried by and pivoted to the 25 hammer C. This hammer C, which on the depression of the corresponding key is adapted to strike the string l, is pivoted in any usual way to the longitudinal bar D, the rear end or head of the hammer being supported when it 30 falls back by the padded pin q, fixed to the end of the key.

To the cross-bar D is fixed a plate, t, which carries at its lower end an adjustable stop, p, for each lever b. This plate t also carries a 35 spring, c, having at its inner end the stop or support d for each rod a. The action of this spring is regulated by a suitable screw, e.

When the key is pressed and its inner end consequently raised, the hammer C is caused 40 to rise and strike the string l through the action of the rod a. At the same time the horizontal arm of the lever b comes into contact with the stop p, and being held back thereby the vertical arm of the lever b presses against 45 the rod a, so as to cause the latter to slide off the stop o. In consequence the hammer C falls back from the string onto the support q, and when the key is left free onto the stationary cross-bar E. The stop d on the spring c, pressing 50 against the projection a' of the rod a, prevents the latter from being thrown too far

when the key is struck violently, and also causes the return of the rod a onto the stop o when the key is released.

In the construction illustrated in Fig. 2, I 55 have shown the spring c and its stop d, and also the stop p, as carried by a bar, S, on the fixed cross-bar E, and the position of the lever b is accordingly reversed.

In order to make sure that the rod a and 60 lever b shall always be in line, a pin or arm, f, on the rod may be adapted to a slot in the lever b, as illustrated in Fig. 2; or a curved finger, f', on the lever may be adapted to a slot in the rod, as illustrated in Figs. 2^a and 3^a. 65

To regulate the action of the spring c, the latter may be carried by a knife-edged block, e', Figs. 2 and 3, adjustably secured by set-screws. The vertical arm of the lever b is in any case curved on its inner face, as illustrated 70 in the drawings, and a correspondingly curved projection, a', on the rod a is provided in order to insure the hammer's falling back from the strings, even when the keys are pressed quite slowly.

If desired, springs G G' may be provided, one adjustably mounted on the hammer C and the other adjustably mounted on the rod a and connected to each other, so that by the adjustment of these springs the action may be 80 rendered easy or hard—that is to say, the springs can be adjusted so as to more or less counterbalance the hammer C, to give an easy action, or, on the other hand, to tend to draw the hammer C downward, with the effect of 85 making the action harder.

The lever b is so made of wood that the fibers of the wood shall lie parallel to the smooth surface on which the lower end of the rod a slides, so that the step o will always remain 90 smooth and not be affected by the action of moisture, as where the ordinary cross-grain is employed. The motion of the rod will always, therefore, be uniform and regular.

In the construction illustrated in Fig. 3 the 95 described mechanism will be understood without further explanation; but in connection therewith I have shown a mute or dampening action. The mute k for the string l is carried by a lever, i, pivoted to a bar, u, fixed on the 100 cross-bar D. The mute-lever is pressed against the strings by means of springs v. The lower

end of the lever *i* is pivoted to a link, *h*, which is provided with an adjustable cushion, *h'*, bearing against the inclined face of a projection, *d'*, on the raising-rod *a*. The link *h* is 5 preferably, also, provided with a guide-pin, *h''*, passing through a corresponding slot in the rod *a*, and serving to prevent the link *h* from moving sidewise.

It will be understood that when the rod *a* is 10 raised by the mechanism described with reference to Figs. 1 and 2 the projection *d'* will push the lever *i* over and raise the mute from the strings. When it is desired to raise all the mutes at once, this can be done by means 15 of a small turning-rod, *z*, hinged to the bar *D*, as usual.

I claim as my invention—

1. The combination of the key of a piano, carrying a pivoted angular lever, *b*, with the 20 hammer *C*, carrying a rod, *a*, a fixed stop, *p*, and a support, *d*, for the lever, all substantially as described.

2. The combination of the key of a piano, and an angular lever, *b*, pivoted thereto, and having a step, *o*, with a hammer having a pivoted 25 rod, *a*, adapted to rest on the said step, which has its fibers parallel with the movement of the rod on the step.

3. The combination of the key, and angular lever pivoted thereto, having a curved face on 30 its upper arm, with the hammer having a pivoted rod provided with a curved face to be acted on by the said lever, as and for the purpose set forth.

In testimony whereof I have signed my 35 name to this specification in the presence of two subscribing witnesses.

AUGUST KAMPE.
